UNITED STATES PATENT OFFICE.

WILLIAM B. ROBINS, OF CINCINNATI, OHIO.

LAMP.

SPECIFICATION forming part of Letters Patent No. 240,462, dated April 19, 1881.

Application filed November 17, 1880. (No model.)

To all whom it may concern:

Be it known that I, WILLIAM BURNET ROBINS, of Cincinnati, Hamilton county, Ohio, have invented a new and useful Improvement 5 in Lamps, of which the following is a specification.

My invention relates to a peculiarly-constructed lamp and a flame-regulating feed-cushion, the same being designed especially 10 for use with one form or other of my mineral candle. The said mineral candle, being the subject of another application for patent to be filed, requires no specific description.

For the above-stated purpose my lamp is 15 constructed with either an annular or a flat candle-holder, according to the form of mineral candle for which it is intended. When constructed for use with the annular or hollow cylindrical form of mineral candle my lamp 20 possesses the wide central draftway, which constitutes one of the characteristics of such candles. The bottom of said holder is supplied with a highly elastic, and at the same time permeable, feed wick or cushion of some springy 25 fibrous or spongy material—such as packed or felted wool, curled hair, worsted yarn, sponge, or “mineral wool,” so called. Associated with such holder, and with its contained feed-cushion and superincumbent mineral candle, is a 30 mechanical device to enable the forcible depression or elevation of the candle, so as either to compress the cushion, and thereby diminish the flow of oil to the candle-top, where alone the combustion takes place, or to permit 35 expansion of the cushion, and thereby enable the more active ascent of oil and corresponding increase of flame.

In the accompanying drawings, Figure 1 is a perspective view of a lamp adapted for use 40 with the annular form of my candle, a portion of the font being broken away. Fig. 2 is a partly-sectioned elevation of the same, showing my feed-cushion and candle in position. Fig. 3 shows the annular or hollow cylindrical 45 form of my candle. Fig. 4 is a partly-sectioned elevation of a lamp embodying a modification of my candle-adjusting mechanism. Fig. 5 is a front view, and Fig. 6 is a side elevation, of a wall-lamp embodying nearly the same form 50 of adjusting mechanism as Fig. 4. Figs. 7 and 8 are axial sections, and Fig. 9 is a partly-sec-

tioned elevation of lamps representing other modifications of the candle-adjusting device. All of the above-represented lamp modifications are adapted for use with the annular 55 form of my mineral candle. Fig. 10 is a perspective view of a lamp adapted for use with the flat form of my mineral candle, a portion of the font-wall being broken away, so as to expose parts of the feed-cushion and superincumbent portion of the mineral candle. Fig. 11 is a transverse section of such a lamp adapted for use with a single central adjusting-screw.

For use with the annular form of my mineral candle the font A is likewise annular, as shown in Figs. 1 and 2, and in Figs. 4 to 9, inclusive, while for use with the flat form of my mineral candle the font is straight, as shown in Figs. 10 and 11.

B represents the customary screw-capped feed-neck.

The front wall, C, of the candle holder or socket C D extends downward into the font, and has oil-passages c. The bottom of the candle-holder is packed with or receives my elastic feed wick or cushion E, composed either wholly of some springy, fibrous, or spongy material or such material associated with an embedded metallic spring, preferably of helical 75 form, as shown at e, Fig. 7.

For the material of the cushion proper I employ, either separately or any two or more of them combined, any suitable pervious and springy material—such as sponge, mineral 85 wool, packed or felted wool, curled hair, or worsted yarn.

Resting upon the cushion E is my rigid mineral candle F, either of annular form, as in Figs. 2, 3, 7, 8, and 9, or flat, as in Figs. 10 and 11. The mineral candle employed by me (and which I intend to be the subject-matter of an application for patent) may be described, briefly, as a core or central lamina, f, of bibulous paper, or other suitable wick material 90 whose vertical surfaces are everywhere incrusted with a wall or coating of a magma or compost of powdered chalk or other mineral or minerals, and a mucilaginous or other bond insoluble by, and impervious to, mineral oil.

A simple form of lamp adapted for the annular form of such candle is represented in

Fig. 1. In this form of lamp the outer wall, C, of my candle holder or socket is pierced with spiral slots G, for the protruding ends h of a wooden splint or slender rod or pin, H, affixed transversely in the candle, as shown in Fig. 3. The burning-fluid, ascending the central permeable core of the mineral candle, reaches the top edge of the latter, and a match being applied a low and brilliant circle of flame is formed. Should said flame smoke it is a sign that the supply of oil is in excess of that which the burning capacities of the candle can consume. To rectify this it is only necessary to increase the candle-pressure upon the feed-cushion, so as to partially close up the latter's interstices. This is effected by a slight backward or left-hand rotation of the candle by means of the projecting ends h of the rod H. By a still greater retrograde rotation the supply of oil may be sufficiently diminished to nearly or quite extinguish the flame. A contrary movement of the rod, of course, produces opposite effects.

Instead of the above construction I sometimes employ a sleeve, I, Fig. 4, whose screw-threaded spurs J traverse vertical slots K in the outer wall of the candle-socket and enter the substance of the candle.

Depending from sleeve I, and traversing tubes L in the font, is a stirrup, M, through which passes a screw, N, which, being journaled in a cross-bar, O, a right or left rotation of the screw operates to depress or elevate the candle, as the case may be.

Figs. 5 and 6 show a modification of the same arrangement for a bracket-lamp, the font being of D form, and the vertical limbs of the stirrup being carried down outside of the font.

Fig. 7 represents a still further modification, in which the sleeve I' is located internally, and is provided with a cross-bar, P, into which the regulating-screw N is tapped.

Fig. 8 represents a modification of the last named, whose sleeve I'' has spirally-formed slots i and a T-formed stem, Q, by which the sleeve is rotated to right or left. Studs R, projecting from the wall of the draftway, occupy said slots i.

Fig. 9 is a modification of the last-named form, in which the sleeve I''' is external, and is provided with knobs S, by which it may be turned to right or left, so as to elevate or depress the candle.

Fig. 10 shows a form of lamp for adapting my feed-cushion for use with a flat mineral candle.

An encircling frame, T, furnished with screw-threaded spurs J, which enter the mineral candle, has screws N tapped within lugs t that project from it, and by which it can be raised or lowered, precisely in the same manner as described for the manipulation of the annular candle. Instead, however, of two adjusting-screws located at the extremities of the candle, as in Fig. 10, a stirrup, M, may be carried down from the sleeve, as in Fig. 11, at a point opposite the mid-length of the

candle, and may receive an adjusting-screw, N. One limb of this stirrup may occupy a tube, L, in the font.

Should it be found that the flame is of unequal height at the two extremities of the candle-summit, such inequality can be cured by momentary withdrawal of the screw-threaded spur J from the less luminous side and its reinsertion somewhat lower down upon the candle. This effects an equalization of pressure, after which the adjustment can be effected by the central screw only.

In forms employing an adjusting-screw at each extremity, as in Fig. 10, rectification of unequal pressure may be produced, either by a shift of one or more spurs, as above, or by manipulation of one or both adjusting-screws. After such adjustment for equality both screws are manipulated simultaneously for increase or diminution of the flame-line.

Elasticity of the fibrous packing may be aided, either by one or more embedded springs, as at e, or by the introduction, below the packing, of springs U, attached to the under side of or supporting a plate, V. (See Fig. 10.)

W, Fig. 9, represents an open frame-base having stepped edges, to adapt it to fit any sized supporting ring or bracket.

I have illustrated my invention in its adaptation to forms of lamps which are designed for use without a chimney; but such mineral candles and compressible cushions may obviously be used with various forms of lamps employing a chimney.

The illustrations are designed to represent my improvements in the form of sheet metal, but glass or other suitable material may obviously be employed.

In the cylindrical form of my mineral candle the rotary movement of the candle itself may often be advantageously converted into a direct vertical motion by employing an additional sleeve or member therefor, or otherwise limiting the motion of the candle to a vertical direction, and in such case the construction herewith represented in Figs. 1 and 2 may have the slots for reception of ends h of the cross-pin H cut vertically and the spiral slots cut in a superposed sleeve for receiving corresponding stumps affixed to the outer tube of the socket or candle-holder, or attrition of the candle against the feed-cushion may be prevented by an interposed washer of wire-gauze, as indicated at x, Fig. 7.

In my manufacture it may be of much importance to apply the compression and recession force to the candle straight up and down to the constructions shown generally by Figs. 1, 2, 8, and 9, like to the straight pull and easing of Figs. 4, 5, 6, 7, 10, and 11.

In Fig. 9 the superposed additional sleeve tapped with the pins J may be connected with the sleeve I''' by receiving in an annular groove cut in its lower edge the top edge of the sleeve I''' turned inwardly, so as to enter and play horizontally in said groove.

I claim as new and of my invention—

1. In combination with a mineral or rigid candle having a permeable core and a corresponding holder or socket, the elastic permeable feed-cushion E, substantially as set forth.
- 5 2. In combination with a mineral candle and its supporting elastic feed-cushion and the holder or socket of the same, the means, substantially as described, for elevating and depressing the candle, and thereby relieving or 10 compressing the feed-cushion in the manner explained.
3. In combination with candle-holding tube C D, feed-cushion E, and mineral candle F, one or more rods or pins, H or J, which connect said candle with a vertically-adjusting device or screw, substantially as set forth.
4. In combination with font A, candle-holder C D, and feed-cushion E, the rod, splint, or pin H, which extends athwart and through the annular mineral candle F and projects 20 through spiral slots G in the holder-wall, as and for the purpose set forth.

In testimony of which invention I hereunto set my hand.

WILLIAM BURNET ROBINS.
